Primary Examiner — Robert M Spear*Assistant Examiner* — Eliza Bennett-Hattan(74) *Attorney, Agent, or Firm* — Brunet & Co. Ltd.; Robert A.H. Brunet(57) **CLAIM**

We claim the ornamental design for a rail bracket, as shown and described.

DESCRIPTION

FIG. 1 is a perspective view of the rail bracket;

FIG. 2 is a side view thereof;

FIG. 3 is an opposite side view thereof;

FIG. 4 is a front view thereof;

FIG. 5 is a rear view thereof;

FIG. 6 is a bottom view thereof;

FIG. 7 is a top view thereof; and,

FIG. 8 is a perspective view of the rail bracket shown holding a rail.

The shaded lines in the Figures show contour and not surface ornamentation.

The broken lines in the drawing depict environmental subject matter only and form no part of the claimed design.

1 Claim, 5 Drawing Sheets(56)
